UNITED STATES PATENT OFFICE.

WALTER T. GORDON, OF JUNIPER, OREGON.

MACHINE FOR ATTACHING SLATS TO CONVEYER-BELTS.

No. 830,709.

Specification of Letters Patent.

Patented Sept. 11, 1906.

Application filed January 25, 1906. Serial No. 242,706.

To all whom it may concern:

Be it known that I, WALTER T. GORDON, a citizen of the United States, residing at Juniper, in the county of Umatilla and State of Oregon, have invented certain new and useful Improvements in Machines for Attaching Slats to Conveyer-Belts; and I do hereby declare that the following is a full, clear, and exact description thereof, reference being had to the accompanying drawings, and to the letters of reference marked thereon, which form a part of this specification.

This invention relates to a novel machine adapted for use in the manufacture of conveyer-belts for harvesting machinery, grain-handling machinery, and the like and comprising a continuous belt or belts and slats affixed transversely thereto; and the invention refers more specifically to a machine for fastening the slats or other attached parts of a conveyer to the belt or belts thereof. Such other parts mentioned may be the belt-protecting disks located between the slats of the conveyer. The belt or belts referred to may consist of a wide web of canvas, two or more parallel separated belts, or a combination of both.

Other analogous uses for such machine may be found, and the invention is not limited strictly to the specific use here suggested.

The machine shown, in which is embodied my invention, comprises in general terms an anvil in which are formed openings carrying setting-punches (constituting movable parts of the anvil to facilitate feeding the rivets to the work) and arranged to receive the rivets at the outer ends of the punches, which rivets are thereafter advanced to the work by the punches, a rotating cylinder above the anvil between which and the anvil the work is to be passed and provided on its outer cylindric surface with a plurality of pockets adapted to receive the parts to be attached to the conveyer or other part and to carry the same by the rotation of the cylinder to the work between the cylinder and anvil, a riveting punch or punches carried, preferably, by the cylinder reciprocating through said pockets and coacting with the setting punch or punches, means acting on the setting-punches for setting the rivets or thrusting them through the work, and means acting on the riveting punch or punches to upset said rivets after they have been set. The cylinder is given intermittent rotation to feed the

parts to be riveted to the work, which are received by said pockets upon the top of the work, and for arresting the cylinder with one set of riveting-punches in alinement or register with the setting-punches. When the parts to be riveted to the work are slats, they are riveted at the ends thereof or at the sides of the conveyer, so that in this event an operating set of riveting-punches embraces one punch at each end of the cylinder which co-operate with two like-disposed setting-punches. If the slats are to be riveted at their longitudinal centers, an intermediate set of riveting and setting punches will be provided. Preferably, and as herein shown, the anvil has the form of a cylinder made of the same diameter as the riveting-punch-carrying and slat-delivering cylinder, and the cylindric rotative anvil is provided at each end with an annular series of openings in which operate the setting-punches referred to and which constitute movable parts of the anvil. Said setting-punches are normally retracted inwardly beyond the cylindric surface of the anvil as to constitute at the outer ends of the openings pockets to receive the rivets and by which they are thus delivered by the rotation of the anvil in line with the riveting-punches and pockets of the cylinder, to be thereafter thrust through the work preparatory to the upsetting operation.

I have herein shown my machine as designed to thus fasten a slat to conveyer-belts by means of fastening devices made in accordance with my prior United States patent, No. 704,823, granted on the 15th day of July, 1902, and when employing the fastening devices shown in said patent the construction of the parts of the machine is varied from a machine designed to fasten the slats by the use of other forms of rivet-and-washer fastening devices.

The invention consists in the matters hereinafter set forth, and more particularly pointed out in the appended claims.

In the drawings, Figure 1 is a front elevation, with parts shown in section, of a machine embodying my invention. Fig. 2 is an end elevation thereof. Fig. 3 is a vertical section taken on line 3 3 of Fig. 1. Fig. 4 is a detail showing the mechanism for intermittently moving the movable parts of the machine. Fig. 5 is an enlarged detail taken through the anvil and slat-delivering cylinder, showing the manner in which the riveting operation is conducted. Fig. 6 is an en-

larged fragmentary detail showing the mechanism for actuating the riveting and setting punches.

Referring now specifically to the structure which characterizes the machine herein shown, A designates the anvil having the form of a hollow cylinder and is rotative. B designates as a whole the riveting-punch and slat-delivery cylinder located above the anvil. Said cylinder B is also hollow and is provided on its outer cylindric surface with a plurality of longitudinal parallel pockets b, adapted to receive the slats which are to be fastened to the web of the conveyer-belt and to deliver said slats to said belt prior to the riveting operation. The cylinder B is arranged over the anvil A, and the web or belt passes between the same to receive the slats, which are delivered thereto by the upper cylinder, and the slats are fastened to the web or belt at a time when the cylindric faces of the cylinder are closest to each other. The step-by-step advancement or rotation of the cylinders feeds the belt between the same and also delivers the slats successively to the belt.

The conveyer-belt shown is of familiar form, it consisting of two or more flexible belts or bands C, usually made of leather, a continuous web C', usually made of canvas, and a plurality of slats C'', which are arranged transversely of the parallel belts and the web and are attached thereto by rivets and washers c c', respectively, the latter being herein shown as made in accordance with the invention set forth in my aforesaid prior United States Letters Patent. The washers are made conical and fit conical sockets in the slats, entering said sockets from the outer faces thereof, and the rivets are designed to be passed outwardly through the belts into the smaller ends of the conical washers and upset therein.

The hollow cylindric anvil A is provided at its ends with thickened parts or rings a, (shown more clearly in Figs. 1 and 6,) in which are formed a series of annularly-disposed radial openings a', Figs. 5 and 6, one series at each end, in which are seated and through which reciprocate a series of radially-disposed setting-punches D. Said setting-punches are provided with square outer ends and are adapted to be normally retracted to their inner positions, with their inner ends a distance inside the cylindric outer surface of the anvil, by means of spiral expansively-acting springs d, surrounding the same and interposed between the inner cylindric surface of the anvil and the heads d' of said setting-punches. The setting-punches D are arrested in their retracted positions, in which they are held by the action of the springs d by means of set-screws d'', having screw-threaded engagement with the thickened or ring end portions of the cylinder and entering keyways d''' in said punches. There

are a number of said sockets a' in the rotative cylindric anvil A, equal to the number of the pockets b of the cylinder B. The withdrawal of the punches D, with their ends inside the exterior surfaces of the cylindric anvil, constitutes pockets in which are placed the rivets before each set of setting-punches reach the riveting positions. When said setting-punches reach their operative positions, which is at the top of the rotative anvil in the present construction, the punches are advanced to thrust the rivet through the belt and web and into the smaller ends of the washers, and the rivets are held in position by said punches while they are upset. It will be observed that the conical washers of the rivets extend practically through the slats, and the smaller ends thereof are sharp, so that when the rivets are advanced by the setting-punches the forward ends of the rivets and the sharpened ends of the washers constitute, in effect, dies which serve to facilitate the cutting of cores from the work, and thus form holes to receive the rivets, the cores being forced into the washers.

The riveting-punches E, which upset the ends of said rivets, occupy and reciprocate in radial openings b', formed in thickened portions or rings b'' at the ends of the upper cylinder, as more clearly indicated in Figs. 5 and 6, the punches of each set being in line with the pockets b. Said riveting-punches extend with their inner or headed ends within the interior of the hollow cylinder B and are adapted to be held in their retracted positions by means of spiral springs e, surrounding the same and interposed between the inner surface of said cylinders and the heads e' of the riveting-punches. Suitable stops are provided for limiting the rearward movement of said riveting-punches under the action of the springs, comprising, as herein shown, set-screws e'', having screw-threaded engagement with the ring portions b'' of said cylinder and engaging recesses e''' in said riveting-punches, as more clearly shown in Fig. 6. The advance ends of said riveting-punches are reduced, as shown at e'', and said advance ends of the punches are guided in the reduced inner ends of the openings b' and are adapted when projected in their outermost positions to extend into the ends of the pockets b of the cylinder sufficiently far to properly engage the rivets of the slats then occupying said pockets. The outer ends of said openings b' within the slat-pockets b are surrounded by conical projections b'', said projections engaging the larger ends of the conical washers in a manner to properly center and hold the slats in the pockets when the slats are delivered thereto in the manner to be hereinafter described. The advance ends of the riveting-punches are preferably roughened or made with cross-cutting edges in order to facilitate the reduction of the cores

cut from the work during the setting operation and also to facilitate the upsetting of the rivets.

It will be observed that the thickened ring 5 portions of the cylinder and anvil constitute the effective portions thereof, so that while said thickened end portions are herein shown as being connected by an integral tube portion it is evident that the connection of said 10 rings may be otherwise effected. It is to be furthermore observed that for some kinds of work a cylinder having a single annular series of coacting punches may be employed, thereby shortening the cylinder.

15 The rotating anvil A and the cylinder B are so mounted and actuated as to be rotated step by step, so as to bring the riveting and setting punches severally into line or operative position, and between such steps of rotation the riveting and setting punches are actuated to first thrust a rivet or rivets through the work, and thereafter the riveting-punch is advanced upon the end of said rivet or rivets in a manner to upset the same, 25 said rivets being held in position during their riveting by the setting-punches. Any suitable means may be employed for mounting the two cylinders, whereby they may be thus intermittently rotated and arrested with upper and lower pairs of punches in coactive alinement and for delivering the slats to the upper riveting-punch cylinder. The means herein shown for so mounting and actuating said cylinders are made as follows: The cylinders A and B are fixed to axial shafts A' 30 B', which latter have bearings at their ends in end frames F F of any suitable construction. Said end frames are connected together at their lower ends by a connecting-bar F'. The members may be connected together at their upper ends by a like bar or bars, or the transverse operating-shafts may be relied upon to hold them together. The shafts A' B' are provided at their adjacent 35 ends at one end of the machine with intermeshing gear-wheels A² B², and one of the shafts, the shaft B', as herein shown, is associated with means for imparting thereto an intermittent or step-by-step rotary motion, 40 thereby imparting to both the shafts A' B' and the cylinders A and B intermittent or step-by-step rotary motion for the purpose stated. Such actuating mechanism is operatively associated with means for locking the 45 cylinders in their arrested positions, whereby the coacting sets of punches are maintained positively in line during their operation. The means herein shown for effecting such intermittent or step-by-step rotary motion and for locking the parts stationary 50 consists, essentially, of a mechanical movement known as a "Geneva movement." It comprises a disk G, that is fixed to one end of the shaft B' of the cylinder B, and is provided 55 on its periphery with a plurality of radial

notches g and intervening peripheral depressions g'. Coöperating with said disk is a continuously rotative disk G', fixed to a shaft G², that extends transversely across and has bearing in the frame of the machine. The disk is 70 provided with an eccentric portion carrying a pin g², which enters one of said radial peripheral notches g once during each rotation of the shaft, and thereby acts to turn the said disk G and shaft B' through a predetermined 75 angular displacement required for bringing the coacting riveting and setting punches in coactive line with each other. After said pin leaves said slot g in the continued rotation of the disk G the disk is locked from further rotation by engagement of the cylindric part of the periphery of the disk G' with the peripheral depressions of the disk G. The means herein shown for rotating said disk G and its shaft B' are made as follows: H designates a main driving-shaft that extends 80 transversely across the top of the machine and is provided at one end with a belt-wheel H' and at its other with a beveled pinion h. Said beveled pinion h meshes with a like 85 beveled pinion 'h, that is affixed to one end of an oblique shaft H², mounted in suitable brackets f' f', extending laterally from the adjacent end member of the machine-frame. Said shaft H² is provided at its lower end 90 with a beveled pinion h², that meshes with a beveled pinion g³, carried on the shaft G² inside the disk G'. In this manner the shaft G² and disk G' are continuously rotated, and the said disks G' G operating in the manner 95 described to intermittently rotate the cylinders and lock the same stationary between their periods of intermittent rotation.

As before stated, the belts C of the web C', of which the conveyer is to be made, are fed 105 between the rotating anvil and the slat-delivering and riveting-punch-carrying cylinder, with the belts C' in line with the setting and riveting punches at the ends of the cylinders. During the time the cylinders are 110 rotating said riveting and setting punches are held in their retracted positions by their springs e and d, said punches being retracted sufficiently to admit the slats to the pockets b of the cylinder B and to admit the rivets to 115 the outer ends of the openings a' of the rotating anvil. After the cylinders have been brought to a state of rest, with the opposed pairs of plungers in line with each other, as 120 stated, and during the time the cylinders are maintained in such state of rest the mechanism is set in motion for setting the rivets and upsetting the same in the manner before stated. The means herein shown for effecting this result are made as follows:

125 Located at each end of the machine outside of the frame members F are two generally parallel vertical bars I I'. Said bars I I' carry at their lower ends followers I² I³, which extend into the hollow ends of the cyl- 130

inders for operative engagement with the punches. The followers I^2 coöperate with the setting-punches D and the followers I^3 with the riveting-punches E. Said bars I I' are adapted to be reciprocated through the medium of suitably-formed cams and in such manner that the bar I' and its follower I^3 are first forced upwardly into their operative positions and the bar I and its follower I^2 there-
10 after forced downwardly into their operative positions, the lower follower being held for a time in its uppermost position while the riveting-punches are being advanced, so as to constitute the setting-punches at this time
15 stationary abutments, which receive the riveting pressure, and when said followers are retracted the springs d and e restore the punches to their retracted positions. Said bars I I' are actuated by cams h^3 h^4 , arranged
20 in opposing pairs on each end of the driving-
shaft H. The upper ends of the bars I I' are provided with suitably-shaped straps i i' , within which the cams h^3 h^4 operate. The cams are of course so arranged as to hold
25 separated the followers during the time the cylinders are rotated, so as to move the followers out of the path of the headed ends of the punches at such time. The straps i i' , in which said cams operate, are provided on
30 their inner cam-bearing surfaces with notches i^2 i^3 to permit the bars I I' to suddenly shift endwise, under the action of the springs d and e , and the followers to suddenly separate when the cams strike said notches,
35 and said notches are so disposed that such sudden separation of the followers takes place at the completion of the upsetting movement of the riveting-punches and just before the cylinders are turned another par-
40 tial rotation.

Any suitable means may be employed to deliver the slats to the pockets b of the upper cylinder B, or the slats may be delivered thereto by hand. As herein shown, said slats are delivered to said pockets at the upper side of the cylinder through a suitable chute J, that is arranged to register with the uppermost pocket of the cylinder B when the latter is brought to a rest. Such delivery takes place by gravity from said chute at a time when the upper cylinder is stationary. Curved guard-bars J', attached at their upper ends to said chutes and extending around the cylinder at the one side thereof, to the
50 lower side of the cylinder, hold the slats in said pockets during the time the slats are being carried downwardly in said pockets on the descending side of the cylinder. Two of such guard-bars, one at each end thereof, are
55 preferably provided.

Any suitable means may be employed for positively advancing the conveyer between the cylinders as it is being formed. As herein shown, the interlocking connection of the
60 slats with the pockets b is availed of to effect

such positive feeding movement. For this purpose an idle roller K is located in front of the cylinders A and B and adjacent to the rising side of the cylinder B, whereby the formed conveyer is held engaged with the upper cylinder and the slat last fastened in place interlocked with one of the pockets until the slat next in rear is fastened in place.

It will be understood that many of the structural details of the machine may be considerably varied without departing from the scope of my invention, and I do not wish to be limited thereto except as hereinafter made the subject of specific claims.

I claim as my invention—

1. A machine for the purpose set forth comprising an anvil, embracing endwise reciprocating setting-punches, a hollow rotative cylinder between which and the anvil the work is advanced and provided on its exterior cylindric surface with a plurality of pockets, a plurality of riveting-punches carried by and rotative with said cylinder and adapted to reciprocate through said pockets and to coöperate with the setting-punches and a single actuating device within the hollow cylinder for severally actuating said riveting-punches.

2. A machine for the purpose set forth comprising an anvil, embracing endwise reciprocating setting-punches, a hollow rotative cylinder between which and the anvil the work is advanced, and provided on its exterior cylindric surface with a plurality of pockets which are adapted to be severally brought into line with the setting-punches by rotation of the cylinder, a plurality of riveting-punches carried by and rotative with said cylinder and adapted to reciprocate radially through said pockets to coöperate with said setting-punches, and a single actuating device within the hollow cylinder for severally actuating said riveting-punches.

3. A machine for the purpose set forth comprising an anvil, embracing endwise reciprocating setting-punches, a rotative cylinder between which and the anvil the work is advanced and provided on its exterior cylindric surface with a plurality of pockets which are adapted to be severally brought into line with said setting-punches by rotation of the cylinder, riveting-punches coacting with said setting-punches and adapted to reciprocate through said pockets, and means acting to force said setting-punches and riveting-punches endwise toward each other, constructed to first advance the setting-punches and to hold them stationary during the advancement of the riveting-punches.

4. A machine for the purpose set forth comprising an anvil, embracing endwise reciprocating setting-punches, a hollow rotative cylinder between which and the anvil the work is advanced, said cylinder being provided on its exterior cylindric surface with a

plurality of pockets, a plurality of riveting-punches carried by and rotating with the cylinder and adapted to reciprocate through said pockets for co-operation with the setting-punches and a single actuating device within the hollow cylinder for severally actuating said riveting-punches.

5. A machine for the purpose set forth comprising an anvil, embracing endwise reciprocating setting-punches, a rotative cylinder between which and the anvil the work is advanced and provided on its exterior surface with a plurality of pockets, riveting-punches carried by and rotating with the cylinder and adapted to reciprocate through said pockets, means for imparting to said cylinder a rotative step-by-step movement to bring said pockets and riveting-punches into line with the setting-punches, and means acting on said riveting and setting punches to move the same toward each other between the step-by-step periods of movement of said cylinder constructed to first advance the setting-punches and to hold them stationary during the advance movement of the riveting-punches.

6. A machine for the purpose set forth comprising an anvil embracing endwise reciprocating setting-punches, a rotative cylinder between which and the anvil the work is advanced and provided on its exterior surface with a plurality of pockets, a series of radially-arranged riveting-punches carried by said cylinder and adapted to reciprocate through said pockets, means for rotating said cylinder step by step to bring said punches and pockets successively into line with the setting-punches, means acting between the steps of movement of said cylinders for advancing said punches toward each other, and means for retracting said punches when released from said advancing means.

7. A machine for the purpose set forth comprising a rotative cylindric anvil and embracing a plurality of radially-reciprocating setting-punches, a rotative cylinder between which and said anvil the work is advanced and provided on its outer surface in line with said setting-punches with a plurality of pockets and carrying riveting-punches adapted to reciprocate through said pockets, means for rotating said anvil and cylinder to bring said setting-punches and riveting-punches into alinement with each other, and means thereafter acting to advance alined riveting and setting punches toward each other.

8. A machine for the purpose set forth comprising a rotative anvil, embracing a plurality of radially-reciprocating punches, a rotative cylinder between which and the anvil the work is advanced and provided on its outer cylindric surface with a plurality of pockets, a plurality of radially-reciprocating riveting-punches carried by said latter cylinder

der and reciprocating through said pockets, means for rotating said cylinders step by step to bring said riveting and setting punches into alinement and means acting between said step-by-step movements of the anvil and cylinder to advance said riveting and setting punches toward each other.

9. A machine for the purpose set forth comprising a rotative anvil provided with a plurality of radial openings reciprocating setting-punches occupying said radial openings, a rotative cylinder between which and the anvil the work is advanced, and provided in its outer cylindric surface with a plurality of pockets, a plurality of radial riveting-punches carried by said cylinder and adapted to reciprocate through said pockets, means for intermittently advancing said anvil and cylinder for bringing the riveting and setting punches severally into line with each other, means acting between such intermittent movements to advance the alined riveting and setting punches toward each other, said punches of the anvil being normally retracted with the outer ends thereof a distance inside of the outer ends of the radial openings occupied thereby, thereby forming pockets to receive the rivets whereby said rivets are delivered to the work.

10. A machine for the purpose set forth comprising a rotative anvil provided with a plurality of radial openings, reciprocating setting-punches occupying said radial openings, means whereby said setting-punches are retracted to provide at the outer ends of said openings pockets to receive the rivets, a cylinder between which and the anvil the work is advanced, a plurality of radially-reciprocating riveting-punches carried by said cylinder, means intermittently rotating said cylinder and anvil to bring the riveting and setting punches severally into coactive line with each other, and means thereafter acting to first advance the setting-punches to thrust the rivets through the work, and to thereafter advance the riveting-punches to upset the ends of the rivets.

11. A machine for the purpose set forth comprising a rotative anvil provided with a plurality of radial openings, reciprocating setting-punches occupying said radial openings, means whereby said setting-punches are retracted to provide at the outer ends of said openings pockets to receive rivets, a cylinder between which and the anvil the work is advanced, a plurality of radially-reciprocating riveting-punches carried by said cylinder, means for intermittently rotating said cylinder and anvil to bring the riveting and setting punches severally into line with each other, and means thereafter acting to first advance the setting-punches to thrust the rivets through the work, and thereafter advance the riveting-punches to upset the ends of the rivets, said punch-actuating mechan-

ism being constructed to permit sudden separation of said punches.

12. A machine for the purpose set forth comprising a rotative anvil provided with a plurality of radial openings, reciprocating setting-punches occupying said radial openings, means whereby said setting-punches are retracted to provide at the outer ends of said openings pockets to receive rivets, a riveting device between which and the anvil the work is advanced and embracing a plurality of riveting-punches which coöperate with said setting-punches for the purpose set forth.

13. A machine for the purpose set forth comprising a hollow, rotative anvil provided with a plurality of radial openings, reciprocating setting-punches contained within said radial openings, springs for normally retracting said punches with their outer ends inside the outer ends of said radial openings, thereby constituting pockets to receive the rivets and in which the rivets are delivered to the work by the rotative movement of the anvil, a hollow cylinder between which and the anvil the work is advanced and provided with a plurality of exterior pockets, a plurality of radial riveting-punches adapted to reciprocate through said pockets, cam-actuated followers extending into said hollow cylinders and adapted to engage the inner ends of said punches to force them into their riveting positions, and springs for retracting said setting and riveting punches after they are released from said followers.

14. A machine for the purpose set forth comprising an anvil embracing reciprocating setting-punches, a cylinder between which and the anvil the work is adapted to be advanced and provided with a plurality of longitudinally-disposed exterior pockets designed to receive slats and with riveting-punches which coöperate with said setting-punches, means for rotating said cylinder step by step to bring the riveting-punches severally into line with said setting-punches, a chute at the upper side of said cylinder for delivering slats by gravity to said pockets, guards for holding said slats in said pockets during the rotation of the cylinder, said pockets delivering the slats between the cylinder and anvil, and means operating between the step-by-step periods of rotation of said cylinder for advancing the riveting and setting-punches toward each other.

15. A machine for the purpose set forth comprising an elongated rotative anvil, an elongated rotative cylinder between which and the anvil the work is adapted to be passed, said anvil being provided at each end with an annular series of radial openings, a plurality of radially-reciprocating setting-punches therein, said cylinder being provided with a plurality of exterior pockets, a plurality of radially-reciprocating riveting-punches carried by said cylinder at the ends

of said pockets and in line with the setting-punches, means for angularly advancing said cylinder and anvil step by step to bring the riveting-punches severally into line with the setting-punches, and means acting between the steps of said anvil and cylinder for advancing the riveting and setting punches toward each other.

16. A machine for the purpose set forth comprising an elongated, hollow, cylindric, rotative anvil provided at each end with an annular series of radial openings, a plurality of endwise-reciprocating setting-punches in said opening, a hollow cylinder, between which and the anvil the work is adapted to be advanced, an annular series of radially-reciprocating riveting-punches located at each end of the said cylinder and adapted to coöperate with said setting punches, means for imparting a step-by-step rotation to said cylinder and anvil to bring the setting and riveting punches severally into coactive alinement, followers extending into the ends of said hollow cylinder and anvil adapted to engage said inner ends of the riveting and setting punches, and cams acting to force said followers together while the cylinder and anvil are stationary.

17. A machine for the purpose set forth comprising a cylindric rotative anvil provided with a plurality of radial openings reciprocating setting-punches occupying said radial openings, a rotative cylinder, between which and the anvil the work is advanced, a plurality of radially-reciprocating riveting-punches carried by said rotative cylinder, a plurality of pockets on the exterior surface of said cylinder through which said riveting-punches reciprocate, means for feeding the parts to said pockets that are to be riveted to the work, means for imparting a step-by-step rotation to said cylinder and anvil for severally bringing the riveting and setting punches in coactive alinement and a roller located at the advanced sides of said cylinder and anvil for holding the work in contact with said cylinder after it has passed between the cylinder and anvil.

18. A machine for the purpose set forth comprising a cylindric hollow anvil provided with a plurality of radial openings, endwise-reciprocating setting-punches located in each opening, said setting-punches being normally retracted to provide at the ends of said radial openings pockets to receive rivets whereby the rivets are delivered to the work, reciprocating riveting-punches coöoperating with said setting-punches and means for operating said punches, constructed to first advance the setting-punches to thrust the rivets through the work and to hold the setting-punches stationary during the advance movement of the riveting-punches.

19. In a machine for the purpose set forth, the combination of a slat-delivery cylinder,

means for automatically delivering slats to said cylinder, an anvil and coacting riveting and setting punches carried by said cylinder and anvil, respectively.

5 20. In a machine for the purpose set forth, the combination of a rotary cylinder provided with pockets for receiving the parts which are to be riveted to the work and in which said parts are delivered to the work by 10 rotation of the cylinder, an anvil, coacting riveting and setting punches carried by said cylinder and anvil, and means for operating

said punches, acting to first advance the setting-punches and to hold them stationary during the advance movement of the riveting-punches. 15

In testimony that I claim the foregoing as my invention I affix my signature, in presence of two witnesses, this 17th day of January, A. D. 1905.

WALTER T. GORDON.
